UNITED STATES PATENT OFFICE.

EDWIN A. JACKSON, OF NEW YORK, N. Y.

DESIGN FOR A FIRE-PLACE FRONT.

SPECIFICATION forming part of Design No. 16,135, dated June 23, 1885.

Application filed January 24, 1885. Term of patent 31 years.

To all whom it may concern:

Be it known that I, EDWIN A. JACKSON, a citizen of the United States, residing at New York, in the county of New York and State of New York, have invented a Design for Fire-Place Fronts; and I do declare the following to be a full, clear, and exact description of the invention, such as will enable others skilled in the art to which it appertains to make and use the same, reference being had to the accompanying photograph, and to the letters and figures of reference marked thereon, which form a part of this specification.

The accompanying photograph fully illustrates my design for a fire-place front, in which the letters A A indicate the side uprights of a frame, each of said uprights being ornamented by a vine and leaves. Between the tops of these uprights is an open-work frieze, A', of vines and leaves. Between the uprights, at their lower ends, is a grate, B, consisting, mainly, of a series of vertical undulating or serpentine bars, b, at each end of which series are horizontal parallel bars c, curving outward

from the uprights to said vertical bars. Below the grate is an ash-pit screen, D, having its front intermediate portion ornamented by an open-work panel, d, of scroll-work.

I claim—

1. The herein described and shown design for a fire-place front, consisting of the vine-ornamented uprights, the open-work frieze of vines and leaves, the grate with its series of vertical undulatory or serpentine bars and horizontal side bars, and the ash-pit screen having its intermediate portion ornamented by an open-work panel, substantially as shown.
2. In a design for a fire place front, the vine-ornamented side uprights and the intermediate frieze ornamented by vines and leaves, as shown.

In testimony whereof I affix my signature in presence of two witnesses.

EDWIN A. JACKSON.
